TAPE DISPENSER

Alexander J. Stanley, North Brunswick Township, Middlesex County, and James Shane Nicholls, Jr., Kingston, N. J., assignors to Industrial Tape Corporation, a corporation of New Jersey

Application August 4, 1948, Serial No. 147,926

Term of patent 14 years

(Cl. D74—1)

To all whom it may concern:

Be it known that we, James Shane Nicholls, Jr., and Alexander J. Stanley, citizens of the United States, residing at Kingston, in the county of Somerset and North Brunswick Township, in the county of Middlesex, respectively, and State of New Jersey, have invented a new, original, and ornamental Design for a Tape Dispenser, of which the following is a specification, reference being had to the accompanying drawing, forming a part thereof, in which

Fig. 1 is a perspective view of a tape dispenser, showing our new design;

Fig. 2 is a rear end view thereof;

Fig. 3 is a side view thereof;

Fig. 4 is a front end view thereof;

Fig. 5 is a top plan view; and

Fig. 6 is an enlarged vertical section on line 6—6 of Fig. 3.

We claim:

The ornamental design for a tape dispenser, as shown.

ALEXANDER J. STANLEY.
